Des. 242,082
Patented Oct. 26, 1976

242,082

STACKING CONTAINER OR THE LIKE

James C. Carroll, Bartlesville, Okla., assignor to Phillips
Petroleum Company, Bartlesville, Okla.

Filed July 29, 1974, Ser. No. 492,833

Term of patent 14 years

Int. Cl. D3—99

U.S. Cl. D87—1 R

FIG. 1

F/G. 3

FIG. 4

FIG. 5

FIG. 9

FIG. 8

FIG. 7

FIG. 6

FIG. 10

FIG. II

FIG. 12

FIG. 13

FIG. 1 is a top perspective view of a stacking container showing my new design;

FIG. 2 is a top plan view;

FIG. 3 is a side elevational view;

FIG. 4 is an end elevational view;

FIG. 5 is an end elevational view showing the end opposite that seen in FIG. 4;

FIG. 6 is a fragmentary, enlarged sectional view taken on the line 6—6 of FIG. 4;

FIG. 7 is a fragmentary, enlarged sectional view taken on the line 7—7 of FIG. 4;

FIG. 8 is a fragmentary, enlarged sectional view taken on the line 8—8 of FIG. 4;

FIG. 9 is a fragmentary, enlarged sectional view taken on the line 9—9 of FIG. 4;

FIG. 10 is a side elevational view of another embodiment of my new design wherein the only difference from the embodiment of FIG. 1 is in the side walls as shown;

FIG. 11 is a fragmentary top perspective view of another embodiment of my new design wherein the only

difference from the embodiment of FIG. 1 is in the end walls as shown;

FIG. 12 is an end elevational view of the embodiment of FIG. 11; and

FIG. 13 is an elevational view of the other end of the embodiment of FIG. 11.

I claim:

The ornamental design for a stacking container or the like, as shown and described.
